UNITED STATES PATENT OFFICE.

NATHAN M. LOWER, OF PITTSBURGH, PENNSYLVANIA, ASSIGNOR TO LOCOMOTIVE STOKER COMPANY, A CORPORATION OF PENNSYLVANIA.

COMBINED STOKER AND FEED-WATER PUMP.

Application filed October 15, 1920. Serial No. 417,072.

The invention relates particularly to means for supplying a steam boiler with water and its furnace with fuel. It being known that the quantity of water which may be evaporated in a given boiler is in direct proportion to the quantity of a given fuel consumed in the furnace, the object of the present invention is to provide mechanism for feeding the fuel and water in the approximate proper relative quantities.

An embodiment of the invention is hereinafter described, and is illustrated in the accompanying drawings in connection with the boiler and fire-box of a locomotive.

In the drawings—

Fig. 1 is a detail vertical longitudinal section of a locomotive and its tender, some of the parts being shown in elevation and portions being broken away to show internal construction;

Fig. 2 is a detail rear end elevation of the locomotive;

Fig. 3 is a detail longitudinal section, partly in elevation, of the feed water pump and the driving motor; and

Fig. 4 is a sectional view on the line 4—4 of Fig. 3.

A portion of a locomotive cab is represented at 10, and the back head of its boiler at 11. A portion of the locomotive tender is shown at 12.

Fuel feeding or stoker mechanism is provided for mechanically conveying or delivering the fuel to the fire-box of the locomotive. Any suitable mechanism may be employed for this purpose. In the form of the device chosen to illustrate the invention the fuel feeding mechanism is, as to its general features, substantially the same as that disclosed in my Patent No. 1,371,252, of March 15, 1921, comprising a pair of elevating conduits 13, 14, extending upwardly through the floor of the locomotive cab and discharging at 15, 16, into the fire-box through the back-head 11 of the boiler, each conduit inclosing an elevating screw, as 17. Fuel is delivered to the lower ends of the conduits 13, 14, through a transferring conveyor conduit, represented at 18, and inclosing a conveying screw 19, the conveying conduit being located below the floor of the fuel bin of the tender and receiving fuel therefrom.

The stoking mechanism is operated by a steam motor 20, the piston rod of which is

attached to a rack bar 21, meshing with pinions 22 for driving the elevating screws, and a similar pinion for driving the transferring conveyor screw 19 through the medium of the shaft 23. The details of the stoking mechanism not being of the essence of the invention, are not illustrated, and this mechanism is included in the present application as being typical, the invention being capable of embodiment in connection with any form of stoker for locomotives with which I am familiar.

Water may be fed to the boiler by means of any suitable pump, a simple and efficient device for this purpose being herein shown and comprising a cylinder 24 axially aligned with the motor cylinder 20, the stem 25 of its plunger 26 being attached to the remote end of the rack bar 21. The induction port 27 of the pump is controlled by a spring-seated poppet valve 28, and is connected by means of a pipe 29 with any suitable source of water supply, as the tank carried by the locomotive tender.

The induction port 30 of the pump is controlled by a spring-seated poppet valve 31, and delivers to the boiler through a suitable pipe connection, as 32, the point of connection with the boiler being located as may be desired. For the purpose of illustration this pipe is shown as entering the chamber of the back-head 11.

The fuel feeding mechanism and the pump being both driven by the motor 20, it follows that the rates of delivery of the fuel and the water correspond, and the relative volume of each is determined by the relative capacities of their feeding means. The quantity of water evaporated by the combustion of one pound of coal being substantially uniform, the two feeding mechanisms are so coordinated that the fuel and water are supplied in proportions corresponding with their respective rates of consumption.

The relative rates of feed of the fuel and water may be easily adjusted, and an arrangement for accomplishing this regulation is preferably present as the character of the fuel frequently lacks uniformity.

As a convenient means for securing such regulation with the form of construction shown and described, there is provided a push rod 33, conveniently positioned for use by the operator and shown as extending downwardly through the floor of the locomo-

tive cab, and being connected to one arm 34 of a bell-crank, the other arm 35 of which bears upon a stem 36 projecting through a stuffing box 37, and bearing upon the back 5 face of the induction valve 28. By pushing down the rod 23 to a greater or less extent the induction valve is correspondingly held away from its seat, and the water drawn into the cylinder 24 by the suction 10 stroke of the plunger 26 may in whole or in part be returned through the induction port by the pressure stroke of the plunger. The deck of the locomotive cabin is indicated at A and it will be noted that the engine 20, 15 the pump 24 and the gearing by which the engine drives the pump and the stoker are located beneath the deck A.

While this is a simple and effective means for securing the relative adjustment of the 20 rates of feed of the fuel and water, any other means for accomplishing this result will come within the scope of the invention.

While the invention is shown in connection with a furnace for burning coal, it is applicable to furnaces of other types. 25

I claim as my invention—

1. The combination with a locomotive steam boiler and its furnace, of stoker mechanism including means for positively conveying solid fuel to and projecting the same into said furnace, a feed pump delivering to the boiler, power means for actuating the stoker and pump in timed relation, and means operable during the operation of said 35 stoker for varying the relative amounts of fuel and water delivered to said furnace and boiler respectively.

2. The combination of a locomotive boiler and firebox with a mechanical stoker adapted to elevate and deliver fuel at definite rates 40 to a firebox, and a water feeding pump for delivering water to a boiler at definite rates, of a motor operatively connected with both of said devices for operating the same 45 in timed relation, and means operable during the operation of the motor for varying the ratio between the rates of delivery of fuel and water.

3. The combination with a locomotive 50 provided with a steam boiler and a furnace, of a mechanical fuel conveying and feeding stoker for the furnace, a feed pump deliver-

ing to the boiler, and power means inter-linked with both said stoker and pump for operating the same in timed relation, said 55 means and pump being located beneath the cab deck of the locomotive.

4. The combination with a steam boiler and its furnace, of a pump including a cylinder for supplying water to the boiler and 60 a mechanical stoker for feeding fuel to the furnace, a reciprocating motor comprising a cylinder in axial alignment with the pump cylinder, a plunger in said pump and motor cylinders, a rack bar connecting said plungers, and a pinion meshing with said rack bar for driving said stoker in timed relation with said pump.

5. In combination, stoking means, a water feeding pump of the plunger type, a reciprocating motor, a rack bar connecting the piston rod of said motor with the pump plunger, a pinion meshing with said rack bar for driving said stoking means, and means for varying the relative rates of delivery of the fuel and water. 75

6. In combination with a locomotive boiler and its firebox, of stoker mechanism including conveyor mechanism for delivering solid fuel to and scattering the same in 80 said furnace, a feed pump positively delivering water to the boiler, a steam engine and gearing associated therewith for actuating the stoker and pump in timed relation, and means operable during the operation of the 85 stoker for varying the water delivered to said boiler thereby changing the ratio of fuel and water delivered by stoker and pump mechanism.

7. In combination, a locomotive having a 90 boiler and a firebox, a tender, mechanical stoker mechanism for conveying fuel from said tender to said firebox, a steam engine on one side of said stoker mechanism, a feed pump on the opposite side of said stoker 95 mechanism delivering water to said boiler, power means operated by the engine for actuating the said stoker mechanism and feed pump in timed relation, said steam engine power means and pump being under the cab 100 deck, and manually controlled means for changing the relative amounts of fuel and water delivered to said boiler.

NATHAN M. LOWER.
